UNITED STATES PATENT OFFICE.

WALTER A. FRANTZ, OF CLEVELAND, OHIO.

TIME SWITCH.

Application filed January 21, 1924. Serial No. 687,509.

This invention relates to time switches, and has for its object the provision of a simple, inexpensive, compact and reliable device of this character, whereby an electric switch can be operated at the end of a predetermined adjustable interval; the provision of a device of this character in which the interval can be varied at will, either increased or diminished, at any time during the interval, and regardless of the existing condition of the mechanism; the provision of a device of this character wherein the load caused by the switch is distributed over a wide interval, thus reducing the danger of stopping the mechanism; the provision of a new type of switch; the provision of a single switch having improved provisions for producing a quick make and break; while further objects and advantages will appear as the description proceeds.

A time switch generally includes a clockwork or retarding train driven by a main spring, and my improvement relates to that well known class of devices wherein a single member is turned to operate the switch in one direction, wind the mainspring, start the escapement (or other retarding device) and select the time interval after which the power of the mainspring, in addition to driving the chronometric train, serves to operate the switch in the reverse direction. More specifically my invention constitutes an improvement upon that set forth in the applications of James H. Reichart filed Feb. 17, 1922, and Sept. 19, 1923, Serial Nos. 537,190 and 663,580 respectively.

In the drawings accompanying and forming a part of this application I have shown certain physical forms in which my inventive idea may be embodied, although it will be understood that the same may likewise be embodied in other physical forms so that these drawings are intended to be only illustrative and not limiting. Fig. 1 is a face view of the casing, showing the switch dial; Fig. 2 is a face view of the clockwork and switch, the casing being omitted and the winding key being cut upon the section line 2-2 of Figs. 3 and 4; Fig. 3 is a central sectional view of the mechanism corresponding to the line 3-3 of Figs. 2 and 4; Fig. 4 is an end view of the mechanism, and Figs. 5, 6, 7, 8 and 9 are detail views showing the

successive steps in the operation of the switch; and Fig. 10 is a modification. 55

Describing these parts by the reference characters appearing on this drawing, 1-1 represent the two plates of a clockwork in which is journaled the arbor 2 to which is connected one end of the mainspring 3, the other end of which is fastened to a post 4 of the frame. Rigidly fastened to this arbor is the ratchet wheel 5 beside which is the loosely sleeved gear wheel 6 provided with the pawl 7 operatively engaging the same. Driven by this gear 6 are the various members 8 of the retarding train controlled by any suitable type of escapement, including, for example, the balance wheel 9. Any desired type of chronometric train can be 70 used.

Rigidly secured to one of the plates 1, concentric with the arbor 2 is a circular plate 10 of insulating material, preferably some substance like bakelite, porcelain, vulcanite or the like which can be easily cast, having on its outer surface a pair of concentric metal tracks, 11 and 12, which terminate in suitable insulated binding posts, 14 and 15 respectively. 75

One of the tracks, as 11, preferably subtends a complete circle, but the other, as 12, is discontinuous at one point, being intersected by a radial notch 16 formed in the surface of the plate 10. This notch is preferably formed with abrupt walls and one end of the track 12 ends abruptly thereat. 85

Operatively connected to the arbor 2 is a handle 20 to which is fastened an insulating sleeve 21 of which at least the lower end is squared or otherwise formed to carry with it the contact bar 22. This bar is formed at one end to engage the track 11, and at the other end to engage the track 12, its intermediate portion being formed with a yoke embracing the sleeve 21 in rotating relation. Spring means are employed to press this bar into contact with the tracks, preferably a coil spring 24 embracing the sleeve 21, though this can be supplemented or supplanted by making the bar itself springy. 95

The clockwork here shown is arranged to drive this bar in a clockwise direction, and the track 12 terminates with such relation to the notch 16 that the bar will be snapped suddenly out of contact when it is pressed 105

therein by its spring, as indicated in Fig. 8. The opposite wall of the notch is made square as shown at 25, so that when the bar comes in contact therewith the clockwork 5 will be stopped. To elevate this bar out of the notch upon the reverse movement of the handle the following expedient is shown:

Pivoted to the edge of the plate 10 at the side of the notch opposite the wall 25 is a 10 camming member 28, which may take many forms, but is here shown as a triangular slip of metal having an inclined side 29 which always faces the notch 16 and a pair of right angled sides in the angle of which lies 15 the pivot 30. The length of one of these sides is such that it projects above the track 12 when the cam is turned, as shown in Fig. 6; the length of the other side is immaterial, except that it should be so far extended as to hold the cam normally in the 20 position shown in Figs. 4, 5, 7, 8 and 9. A spring can be added to insure this position.

The connection between the handle 20 and arbor 2 is such as normally to cause them to 25 turn together while permitting relative movement under certain abnormal conditions. In Fig. 3 the arbor is tapered as shown at 32, the hub 33 of the handle being similarly tapered and forced thereon by a 30 spring 34 and nut 35 applied to the reduced end of the arbor. The spring 34 is stronger than the spring 21 and the angle of taper is so chosen that a friction clutch is produced having such a tension as shall enable 35 the winding but not the overwinding of the spring 3, and also permit the switch to be turned back at any time without awaiting the action of the clock mechanism.

In Fig. 10 the arbor 2^a is formed with 40 clutch teeth 36 co-operating with similar clutch teeth 37 formed on the hub 33^a of the handle 20^a. This hub is loosely sleeved on the reduced extension 38 of the arbor 2^a and is normally held clutched to the arbor by the 45 spring 34 and nut 35, this spring as before being of greater strength than the spring 24. This arrangement enables the mechanism to be set like a watch by a slight pull on the stem. The sleeve 21 or 21^a is non- 50 rotatably mounted on an extension of the hub which may either be integral as shown at 36 in Figs. 1 and 2 or separate and pressed or otherwise rigidly secured as shown at 36^a in Fig. 10.

55 The switch and clockwork are preferably housed in a suitable casing 40, the handle 20 being located outside the same and provided with a pointer 41 playing over a dial 42 with which the casing is provided. I have 60 shown a mechanism wherein the arbor 2 has a rate of one complete revolution in two hours, the dial being calibrated accordingly, and the pointer being set to indicate zero time at the instant the bar 22 breaks contact with the track 12. However, the clock 65

does not stop until the bar engages the wall 25 of the notch, at which time the pointer occupies the dotted position shown in Fig. 1, which corresponds with the dotted position of the bar in Fig. 2.

Starting from this point the operation is as follows: The operator turns the handle 20 in the only direction it will go, namely: counterclockwise. The bar 22 first engages the cam 28 and rotates it to the position shown in Fig. 6, whereupon it rides up the inclined face and jumps to the track 12, thereby making a quick contact, after which the cam drops back to its initial position as shown in Fig. 7. The handle is turned until the pointer indicates the length of time during which the current is to be left on, the spring 3 being meanwhile wound up. As soon as the handle is released the clockwork restores it gradually to its initial position, the circuit being quickly broken as the bar jumps from the track into the notch, where it first lands upon the cam as shown in Fig. 8 and later proceeds to the bottom of the notch as shown in Fig. 9. The switch, however, is at all times under the control of the operator. If it be desired to open the circuit previous to the time designated, the releasable connections between the handle and arbor permits this to be done; likewise if by repeated oscillations of the handle the spring 3 be fully wound it is still possible to operate the switch. It is impossible to turn the handle in a counterclockwise direction when the bar 22 occupies the position shown in Fig. 8, but the same must first be turned slightly in a clockwise direction to the position shown in Fig. 9, after which it can be rotated as desired.

It will be understood that I do not limit 105 my improved switch to use solely with time controlled mechanism, as there are certain features of the same which are of broader application; neither do I restrict the use of the resetting mechanism herein solely to 110 switches of this construction; nor do I limit myself to any details of construction, arrangement or design except as specifically recited in my several claims.

Having thus described my invention, what 115 I claim is:

1. In a time switch, a stationary member having a discontinuous circular track terminating in an abrupt shoulder, a movable member adapted to sweep over said track and to jump abruptly from said shoulder, means for rotating said member in opposite directions, and means operative upon the approach of said member toward said shoulder in the opposite direction from which the jump occurred for elevating said member automatically to contact with the track.

2. In a time switch, a circular metal track having a notch and a spring pressed metal member adapted to engage said track and

- to spring from said track into said notch, a chronometer train and a main spring adapted to produce relative movement between said track and member, and connections to said track and said member whereby the switch is abruptly opened when said member springs into said notch.
3. In a time switch, a circular track having a notch and a spring pressed member adapted to engage said track and to spring into said notch, a chronometer train and a main spring adapted to produce relative movement between said track and member, and connections for said member whereby the circuit is abruptly opened when said member springs into said notch and means operative when said members are set back manually for lifting said member out of said notch.
4. An electric switch comprising, in combination, a circular track having a notch, a spring pressed member adapted to run on said track and to spring into said notch, means for effecting relative movement between said member and track, and means operative after said member has sprung into said notch for lifting the same out of said notch upon movement of the parts in the opposite direction.
5. In a device of the character described, in combination, a track having a shoulder, a spring pressed member movable along said track and adapted to spring past said shoulder, and a cam adapted to spring said member back onto said track when it is moved in the opposite direction.
6. In an electric switch, a discontinuous track having an abrupt shoulder, a member movable over said track and yieldingly pressed thereagainst so as to spring therefrom when moved past said shoulder in one direction, and a loosely mounted cam adapted to be engaged by said member when moved toward said shoulder from the opposite direction to elevate said member past said shoulder and onto said track.
7. In an electric switch, a discontinuous track having two portions at different levels separated by an abrupt shoulder, a member movable along said track and yieldingly pressing thereagainst so as to spring abruptly past said shoulder when moved past the same in one direction, connections for breaking the circuit when said member leaves the track at said shoulder, means for producing relative movement between said member and track in both directions, and a cam member pivoted adjacent to said shoulder adapted to restore said member to said track when moved toward said shoulder in the opposite direction.
8. In an electric switch, an insulating base, a discontinuous metal track carried thereby and terminating at one end in an abrupt shoulder, a spring arm adapted to be moved around said track, electric connections to said arm and track whereby the circuit will be broken abruptly when the arm is moved past said shoulder in one direction, and means for automatically snapping said arm back on said track when said arm is moved past said shoulder in the opposite direction.
9. In an electric switch, the combination with a discontinuous track ending in an abrupt shoulder and a spring arm adapted to be moved over said track and to jump from said shoulder, of a cam member pivoted adjacent said shoulder and having a slanting edge adapted to be engaged by said arm when the same is moved in the reverse direction and turned to form an incline up which the arm can move to re-engage said track.

In testimony whereof, I hereunto affix my signature.

WALTER A. FRANTZ.
